Primary Examiner — T. Chase Nelson(74) *Attorney, Agent, or Firm* — Marshall A. Lerner; Marvin H. Kleinberg; Kleinberg & Lerner, LLP**CLAIM**

The ornamental design for a shoe outsole periphery and bottom, as shown and described.

DESCRIPTION

FIG. 1 is a bottom perspective view of a first exemplary embodiment of a shoe outsole periphery and bottom in accordance with my new design.

FIG. 2 is a left side view thereof;

FIG. 3 is a bottom plan view thereof;

FIG. 4 is a bottom perspective view of a second exemplary embodiment of a shoe outsole periphery and bottom in accordance with my new design.

FIG. 5 is a left side view thereof; and,

FIG. 6 is a bottom plan view thereof.

Broken lines showing the remainder of the shoe in the figures are for illustrative purposes only and form no part of the claimed invention.

1 Claim, 6 Drawing Sheets(56)
